UNITED STATES PATENT OFFICE.

CHARLES WEINEDEL, OF LOUISVILLE, KENTUCKY, ASSIGNOR OF ONE-HALF
TO OTTO E. MUELLER, OF SAME PLACE.

SWINGING CAN.

SPECIFICATION forming part of Letters Patent No. 329,247, dated October 27, 1885.

Application filed July 27, 1885. Serial No. 172,745. (No model.)

To all whom it may concern:

Be it known that I, CHARLES WEINEDEL, a citizen of the United States, residing at Louisville, in the county of Jefferson and State of Kentucky, have invented a certain new and useful Improvement in Swinging Cans, of which the following is a full, clear, and exact description.

This invention relates to that class of cans for oil and other fluids which are arranged in a frame or casing and adapted to be tilted or swung therein from an upright to an inclined position to facilitate the outlet of fluid from them.

15 In my invention a combined casing and stand remains stationary at all times and in all operations of the can, and the can is jacketed at top and bottom and front and rear, and is pivoted to swing in the casing upon pins or lugs fixed in the casing, the top and bottom of the can and its jacket being inclined or beveled, the more readily to adapt it to swing in its casing and stand without moving it vertically in the casing to get a bearing for its pivots, and 20 without unduly enlarging the casing and stand, as has been heretofore necessary in permitting the can to swing. In my invention the can is pivoted permanently to its casing, and is held upright therein by any suitable latch or hook, 25 which when released leaves the can free to be swung upon its pivots to discharge its contents.

The invention consists in a swinging can constructed and arranged as hereinafter particularly set forth and claimed.

35 In the accompanying drawings, in the several figures of which like parts are similarly designated, Figure 1 is a perspective view of a can embodying my invention. Fig. 2 is a side elevation of the same with one side of the 40 combined casing and stand removed, and showing the can in its tilted position by dotted lines. Fig. 3 is a top plan view of the can. Fig. 4 is a perspective view of the can and its jacket detached, and Fig. 5 is a perspective 45 view of the stand alone.

The combined casing and stand comprises side pieces, *a b*, the top *c*, the battens *d e*, and a bottom brace, *f*. The top is cut away at *g* to admit access to the nozzle, vent, and handle 50 of the can. The can *h* is of usual material, and

has its bottom and top *i j* respectively inclined and parallel, and its sides are of such length as to permit the top and bottom, when the can is swung or tilted upon its pivots, to describe arcs within the height of the casing 55 and stand. The front and back and top and bottom of the can are provided with strips of wood, *k l m n*, respectively, which, co-operating with the sides *a b* of the casing, constitute a jacket for said can. The front and back pieces, 60 *k l*, of the can have the battens *o p*, respectively at top and bottom, in harmony with the battens *d e* of the casing and stand. The front and back strips, *k l*, come out flush with the sides *a b*, and when the can is upright in its 65 casing and stand this construction has the appearance of a homogeneous outer casing. The can is pivoted in the sides *a b* by means of studs or gudgeons *q q*, which have fixed bearings *t* in said sides, and by means of which the can 70 may be freely swung or tilted within its casing or stand, as clearly indicated by Fig. 2. The can is retained within its casing and stand by a hook, *r*, secured to the top *c* of the casing, and engaging an eye, *s*, on the batten *o*, and when the can is to be tilted, so as to pour out 75 its contents, the hook is disengaged, and the can may be then freely turned upon its pivots.

By my construction the adjustment of the can into and out of bearings for it in pouring 80 and packing, respectively, is obviated, and the top and bottom being beveled, so as to permit the can to freely turn within its casing and stand, I effect a large economy of space in the consequent reduction in size of the article. 85

What I claim is—

1. A can jacketed at front, rear, top, and bottom, and provided with side pivots, combined with a casing and stand having fixed sides, top, and bottom and fixed bearings for 90 the pivots of the can in its sides, substantially as described.

2. A can having its top and bottom inclined in parallel planes and jacketed at front, rear, top, and bottom, and provided with side pivots, combined with a casing and stand having fixed sides, top, and bottom and fixed bearings for the pivots of the can in its sides, substantially as described. 95

3. A can having an inclined top and bottom, 100

- and suitably jacketed, combined with a combined casing and stand rigid throughout, but open at front and rear, and supporting the can in fixed bearings, substantially as described.
5. 4. A can having an inclined top and bottom, and suitably jacketed, combined with a combined casing and stand rigid throughout, but open at front and rear, and supporting the can in fixed bearings, and having an opening in its top for access to the nozzle, handle, and vent of the can, substantially as described.
5. The casing and stand comprising the sides *a b*, top *c*, battens *d e*, and bottom brace, *f*, combined with the can having the jacket *k l m n* and battens *o p*, substantially as set forth. ¹⁵
- In testimony whereof I have hereunto set my hand this 24th day of July, A. D. 1885.

CHARLES WEINEDEL.
